Specification for Design.

Patented May 23, 1922.

Application filed October 20, 1921. Serial No. 509,188. Term of patent 14 years.

To all whom it may concern:

Be it known that I, FRANCIS M. CASE, a citizen of the United States, residing at Cleveland, in the county of Cuyahoga, State of Ohio, have invented a new, original, and ornamental Design for a Combination Washing-Machine Tub and Frame, of which the following is a specification, reference being had to the accompanying drawing, forming part thereof.

The figure is a perspective view of a combination washing machine tub and frame showing my new design.

I claim:

The ornamental design for a combination washing machine tub and frame, as shown.

In witness whereof, I have hereunto set my hand this 14th day of October, 1921.

FRANCIS M. CASE.
